UNITED STATES PATENT OFFICE.

ROBERT L. SHRINER, OF WEEHAWKEN, NEW JERSEY, ASSIGNOR, BY MESNE ASSIGNMENTS, TO WILLIAM PASTERNAK, OF NEW YORK, N. Y.

ELECTRICALLY-OPERATED WATER HEATER.

Application filed January 6, 1927. Serial No. 159,251.

This invention relates to heat exchanging devices and deals more specifically with an automatic water heater for household and other uses.

5 It is an object of this invention to provide an improved electrically operated water heater which is entirely automatic in its control.

10 It is a further object of this invention to provide an improved water heater in which there is an efficient circulation of water.

15 Further, it is an object of this invention to provide an improved heater in which there is an efficient heat transfer at a minimum of heat losses.

20 It is a further object of this invention to provide a water heater comprising few and simple parts which shall be relatively cheap to manufacture, and in which certain of the 25 vital elements may be replaced with a minimum of effort.

Still another object of this invention is to generally improve the structure of water heaters of the character described and to render the same practical and efficient in operation to a high degree.

Other objects of this invention will in part be obvious and in part hereinafter pointed out.

30 The invention accordingly consists in the features of construction, combinations of elements, and arrangement of parts which will be exemplified in the construction herein-after described, and of which the scope of application will be indicated in the following claims.

In the accompanying drawing, in which is shown one of the various possible illustrative embodiments of this invention,

40 Fig. 1 is a cross-sectional view of an electrically operated water heater embodying the invention.

Fig. 2 is a sectional view taken on line 2—2 of Fig. 1.

45 Figs. 3 and 4 are elevational and plan views respectively, of the electric heater element.

Figs. 5 and 6 are fragmentary elevational and plan views, respectively, of a modified form of the invention.

50 Referring in detail to the drawing, the water heater 10 embodying the invention is seen to comprise a cylindrical outer covering 11 formed of any suitable sheet material provided with the closure head 12 forming the joint 13 with the covering and which is se-

cured thereto in any suitable well understood manner. Mounted interiorly of the covering 11 and in spaced relation thereto is a sheet metal casing 15 which is also of cylindrical shape and which is positioned concentric with said covering 11. The covered casing 15 is mounted upon a standard 14. The space between the covering 11 and casing 15 is preferably packed with heat insulating material such as magnesia, asbestos, felt, or the like. The upper end of the casing 15 is provided with a top closure or head 16 which is joined to the casing by means of the lap joint 17, which is either riveted or welded or otherwise suitably secured in water tight relation. A circular base plate 18 is mounted at a substantial distance from the bottom of the casing for forming the water receiver or reservoir A. Said plate 18 has a peripheral out-turned edge portion 18^a which lies in close contact with the casing 15, and may be riveted thereto to provide a water tight joint. 20 indicates an inlet pipe which admits the cold water to the receiver A from a suitable water supply source (not shown) and 21 indicates an outlet pipe through which the hot water is drawn from the receiver. The pipes 20 and 21 are connected to the head 16 by means of flanged fittings 16^a which are joined to the head 16 by welding, rivets, bolts or the like.

Mounted to extend axially with respect to the casing 15 is a second casing 22 provided with a helical ridge 22^a which extends substantially the entire length of the exterior 90 side thereof. Said casing 22 forms a chamber C and is secured to the plate 18 in water tight relation, by means of the outwardly turned flanges 22^b.

The upper end of the casing 22 is provided 95 with a water-tight closure by means of the head plate 26 which has the downwardly turned inner portion 26^a which may have a metallic connection as by soldering with one or more pipes 28 passing through said plate 100 26. Pipes 29 which communicate with the reservoir A through the plate 18 are detachably connected by means of the union couplings 23. Each of the pipes 29 connects with a pipe 30 which extends horizontally outward 105 from the casing 15 where it is provided with a faucet 31 for draining the reservoir A. The pipe or pipes 28 are provided at their lower ends with a manifold 27 and connect with the pipe 30 by a T-fitting 32, the upper end or 110

ends of said pipe or pipes 28 being open and in communication with receiver A. Each pipe 28 is preferably formed of tubing having an interior helical ridge 28^a as shown in Fig. 1. Mounted above the upper ends of the pipes 28 is the baffle plate 34 which is carried by the rod 36, suitably secured in any well known manner between the pipes 28.

Referring to Fig. 3, the electric heater member will be seen to comprise the upper head plate 37 and the lower plate 38, both of which may be circular in shape and are held in fixed relation with respect to each other by the stay bars 39 and the nuts 40. An intermediate circular insulating plate 41 is mounted in spaced relation to the plate 38 as shown and is held in position by the stay bars 39 and the nuts 42. Mounted between the plates 38 and 41, at equal intervals in concentric relation are four heat insulating tubes 43. Passing through the plate 38 and electrically insulated to extend into the tubes 43 are the screws 44, each of which carries the head 45, the latter being adapted to be adjusted longitudinally of the tubes 43 by means of the screws 44. The spiral springs 46 rest upon each of the heads 45 and contacts with heads 47 formed on plungers 48, the latter being adapted to slide through the insulating plate 41. The upper ends of the plungers 48 are formed with the four cup-shaped portions 49 and are adapted to support the lower end of resistance elements 51. Mounted on the plate 37 opposite each of the cup portions 49 are the four cups 50. Each of the latter is adapted to receive the upper ends of one of the resistance elements 51. The resistance elements are preferably made in the form commonly known in the art as "Glow Bar" but other resistance elements may be employed without departing from the spirit of this invention. These elements may be four in number and may be connected in series circuit by means of the jumpers 51^a, 51^b.

The heater member forms a unit as shown in Figs. 3 and 4 which is positioned interiorly of the casing 22 and is removably held in place by the supporting head 24. Said head is detachably secured against the casing flange 22^b and the plate 18 by the bolts 25 and is formed with a passage through which the electric heater unit extends into the chamber C, as shown in Fig. 1. The plates 37, 38 and 41 of the heating unit are provided with centrally aligned openings 37^a, 38^a and 41^a, respectively, which form an axial passage for receiving a pipe or the pipes 28 so that the resistance elements are disposed between said pipe or pipes 28 and the casing 22, as shown in Fig. 1.

Mounted within a lower compartment B under the reservoir A is the block 52 which connects the resistance elements of the heater unit to the current supply source (not shown) through the leads 53. 54 indicates a conven-

tional type of thermostat which may be installed to extend through the casing 15 into the reservoir A and is designed to regulate the operation of the heater in accordance with the temperature of the water. The particular type of thermostat used in the present case forms no part of this invention and any of the thermostats well known in the art may be used. The pipe 55 mounted between the covering 11 and casing 15 serves to carry the leads which connect the heating system to the source of power.

The operation of the apparatus is as follows: Cold water enters through the pipe 20 and fills the reservoir A. Water also fills the pipes 29, 30 and 28. When the temperature of water in the reservoir A falls to a certain predetermined point, the thermostat starts the operation of the heating unit by closing the electrical circuit. Current flows from one of the leads 53 to one of the screws 44 to the connected head 45 to the spring 46 to the head 47 through the plunger 48 to the cup 49 and thence through the resistance element. By means of the jumpers 51^a a series path for the current is made through other resistance elements 51 and we thus have the current flowing from one of the leads through the resistance elements successively and returned to the other one of the leads 53. Thus, it will be seen that the line voltage is impressed on the resistance elements and they are heated to a high temperature. I have found that with the particular material used, namely, "Glow Bar," the resistance elements may be raised to a temperature as high as 2000° F. at which temperature they are brought to incandescence. The heat developed by these elements is transmitted to the pipe or pipes 28 by both radiation and conduction. While the heat is transferred with maximum intensity to said pipes, it is also transferred to the casing 22 and heats the water in the reservoir A.

The circulation of the water results from the well known phenomenon that the density of water is greater at the lower than at the higher temperatures. The circulation therefore follows the following course:

The cold water sinks in the pipes 29 and 30 and thereby passes through manifold 27 to the lower mouths of the heater pipe or pipes 28 where the temperature of the water is raised. This, of course, causes the hot water to rise and consequently the cooler water follows behind, where it in turn is raised in temperature until it passes out of the upper ends of the pipe or pipes 28 into the reservoir A. In order to facilitate and render more efficient the heat transfer between the water and the hot surface with which it contacts the spiral or helical ridges 22^a and 28^a are formed to break the water stream up and give it a mixing and turning action.

When the water in the reservoir has reached

the upper limit of the temperature for which the heater is set, the thermostat opens the main circuit, thus shutting off the current supply. The action of the heater is thereby rendered entirely automatic and hot water of any desired temperature within the usual heater range may be withdrawn through the pipe 21.

In order to simplify the assembly of the apparatus and also the replacement of the parts such as the resistance elements, the chamber B is made of sufficient size to permit the vitals of the heater unit to be dropped sufficiently to permit of ready access to its parts. Thus, when it is desired to replace a resistance element the water need not be drained off nor the water piping disconnected, it being merely necessary to release the heated unit from the supporting head 28 by swinging holding latches 33 in the well understood manner and to drop the unit down. The parts of the unit may then be replaced. Inasmuch as the elements 51 are held between the cups 49 and 50 by means of the springs 46 the operation of replacing one of these elements is extremely simple.

In Figs. 5 and 6 is shown a modified form of the invention in which the shape of the heating pipes 280 as well as the position of the resistance elements 510 with respect to the pipes is changed. The pipes are made in a flattened oval shape as shown and are turned over and expanded to secure them at their upper ends 280^a to the plate 260 of the casing 220 in water tight relation. The lower ends 35 of the pipes 280 may be connected to a manifold (not shown) in the manner similar to the manifold 27 shown in Fig. 1. The resistance elements are disposed at the apices of an equilateral triangle with respect to the tubes 280 and the fourth element is placed in the centre. The resistance elements are connected in series between the plates 370 and 410 with the terminals of the current source in the same manner described above in connection with Figs. 1 and 3. The remaining structure of this modification may be identical with the form described above and needs no further explanation. The operation of this modified apparatus is also the same as that described above. It is merely necessary to point out that by virtue of this modified construction, the structure of the circulating system is simplified.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A water heater comprising a casing forming a reservoir for the water, a casing 70 forming a chamber extending into said reservoir, a head for said chamber mounted to extend exteriorly of said reservoir, circulating pipes passing through said head and said chamber, and communicating with said reservoir, and heating means carried by said head adjacent to said pipes.

2. A water heater comprising a casing forming a reservoir for the water, a casing 80 forming a chamber extending into said reservoir, said chamber casing being provided with a helical ridge extending lengthwise thereof, a head mounted on said tank exteriorly of said reservoir, circulating pipes passing through said head and said chamber, 85 and communicating with said reservoir, and heating means carried by said head adjacent to said pipes.

3. A water heater comprising a casing forming a reservoir for the water, a casing 90 extending into said reservoir, a head for said chamber mounted on said reservoir exteriorly of said reservoir, circulating pipes passing through said head and said chamber and communicating with said reservoir, said 95 pipes being formed with a helical ridge extending lengthwise thereof.

4. A water heater comprising a casing having an upper and a lower compartment, a casing forming a chamber extending into 100 said upper compartment and forming a water reservoir therewith, a head for said chamber disposed in said lower compartment, means to conduct water from said reservoir through said lower compartment, a pipe mounted in 105 said chamber and communicating with said means, and heating means carried by said head and disposed in said chamber parallel to said pipe.

5. A water heater comprising a casing, a 110 plate dividing said casing into an upper and a lower compartment, said plate being formed with a central circular aperture, a casing forming a chamber secured to said plate and extending upwardly through the aperture 115 into said upper compartment, means detachably secured to said plate for conducting the water from said upper compartment through said lower compartment and through said chamber back to said upper compartment, 120 and means demountably secured in said chamber and surrounding said portion of said first mentioned means to heat the water during its passage through the latter.

6. A water heater comprising a casing, a 125 plate dividing said casing into an upper and a lower compartment, said plate having an aperture therein, a casing forming a chamber secured to said plate and extending through said aperture into said upper compartment, 130

means detachably secured to said plate for conducting the water from said upper compartment through said lower compartment and through said chamber back to said upper compartment, a head secured to said plate about said aperture and extending in said lower compartment, and means supported by said head for heating the water during its passage through said chamber.

10. 7. A water heater comprising a casing, a plate dividing said casing into an upper and a lower compartment, said plate having a central circular aperture therein, a cylindrical casing forming a chamber secured to said plate and extending through said aperture into said upper compartment, and a pipe line disposed within said lower compartment and detachably connected to said upper compartment, whereby water may flow through said pipe line from said upper compartment, a pipe communicating with said line passing upwardly through said chamber and opening into said upper compartment at the upper ends thereof, and means mounted within said chamber surrounding said pipe to heat the water passing therethrough.

8. A water heater comprising a casing, a plate dividing said casing into an upper and a lower compartment, said plate having a central circular aperture, a cylindrical casing forming a chamber secured to said plate and extending upwardly into said upper compartment, and a substantially U-shaped pipe line disposed within said lower compartment and detachably connected to said upper compartment, whereby water may flow through said pipes from said upper compartment, a plurality of pipes communicating with said line, passing upwardly through said chamber and opening into said reservoir at the upper ends thereof, a detachable head secured to said plate around said aperture and extending into said lower compartment, and heating means carried by said head surrounding said pipes.

9. A water heater comprising a casing, a plate dividing said casing into an upper and a lower compartment, said plate having a central circular aperture, a cylindrical casing forming a chamber secured to said plate and extending upwardly into said upper compartment, a pipe line disposed within said lower compartment and detachably connected to said upper compartment, whereby water may flow through said pipe line from said upper compartment, a pipe communicating with said line and passing upwardly through said chamber and opening into said reservoir at their upper ends, a heating unit mounted in said chamber, and a head secured to said plate, said unit being supported by said head for sliding movement lengthwise thereof, whereby the unit may be repaired without disassembling the piping system.

10. In a water heater of the class described,

an electrical heating unit comprising an upper and a lower plate, stay bars holding said plates in fixed spaced relation, an intermediate insulating plate held by said stay bars, a plurality of spring members passing through said insulating plate, a plurality of resistance elements held between said upper and lower plates by said members, and means for connecting said elements in an electrical circuit.

11. In a water heater of the class described, an electrical heating unit comprising an upper and a lower plate, stay bars holding said plates in spaced relation, an insulating plate intermediate said upper and said lower plates, insulating tubes held between said insulating plate and lower plate, plungers mounted through said insulating plate and extending into said tubes, a spring in each of said tubes pressing said plungers, resistance elements supported between said plungers and said upper plate, and means to connect said elements in an electrical circuit.

12. In a water heater of the class described, an electrical heating unit comprising a pair of spaced plates, resistance elements removably held between said plates, spring pressed supports at one end of each of said elements whereby said supports may be depressed and the elements removed, and means to connect said elements in an electrical circuit.

13. A water heater of the character described comprising a reservoir having a chamber, a pipe extending through said chamber adapted to circulate water through the reservoir, and a heating unit removably fitted in said chamber surrounding said pipe.

14. A water heater of the character described comprising a reservoir having a chamber, a plurality of pipes in the chamber, the ends of said pipes extending through the walls of the chamber adapted to circulate water through the reservoir, baffling means for deflecting the water passing from said pipe ends, and a heating unit removably fitted into said chamber between the walls of the latter and said pipes.

15. In a water heater of the character described, an electrical heating unit comprising resistance elements, means for holding said elements parallelly spaced, and a water circulating pipe, said means including a through passage for receiving said pipe, said unit being movable along said pipe to facilitate repairs.

16. A water heater of the character described comprising a reservoir having a chamber, a pipe extending centrally through the chamber, the end of the pipe communicating with the reservoir, a baffle plate for deflecting the water passing from the end of the pipe in said reservoir, and heating means in said chamber surrounding said pipe.

In testimony whereof I affix my signature.
ROBERT L. SHRINER.
